(57) **CLAIM**

The ornamental design for a torque increasing wrench attachment, as shown and described.

DESCRIPTION

FIG. 1 is a front elevated view of a torque increasing wrench attachment showing my new design;

FIG. 2 is a left side elevated view of the torque increasing wrench attachment;

FIG. 3 is a right side elevated view of the torque increasing wrench attachment;

FIG. 4 is a top plan view of the torque increasing wrench attachment;

FIG. 5 is a bottom plan view of the torque increasing wrench attachment;

FIG. 6 is a front perspective view of the torque increasing wrench attachment; and,

FIG. 7 is a front cross-sectional view of the torque increasing wrench attachment to show a depth of the openings therein.
